PROCESS OF REFINING PETROLEUM
PRODUCTSEmerson C. Higgins, Jr., West Los Angeles, Calif.,
and Franklin T. Gardner, Tulsa, Okla.No Drawing. Application June 8, 1931,
Serial No. 543,004

11 Claims. (Cl. 196—32)

The present invention relates to an improved process for the purification and refining of petroleum products such as gasoline, kerosene, naphtha, lubricating oils, and the like.

5 One of the objects of the invention is to treat these products, in the liquid state, with a reagent capable of removing therefrom or altering acid substances and sulphur compounds, and to effect this in a single stage of operation and 10 in a substantially continuous manner.

Another object of the invention is to refine and purify such a petroleum product as gasoline which may or may not have been subjected to treatment with acids, such for example 15 as sulphuric acid, by means of a neutralizing but water-insoluble reagent, while at the same time effecting the removal of sulphur compounds from the gasoline or alteration of sulphur compounds in the gasoline.

20 Still a further object of the invention is to treat gasoline containing free acid and sulphur compounds with magnesium hydroxide, preferably in the form of the mineral brucite, and with sulphur, which latter element is dissolved 25 in the gasoline that is undergoing the treatment.

A further object of the invention is to effect the alteration of sulphur compounds, such as mercaptans, in petroleum products by reagents which will form metallic mercaptides by reacting 30 with the said mercaptans, and then treating said mercaptides with an element of the group comprising oxygen, sulphur, selenium, and tellurium, whereby the metallic mercaptide is decomposed into a metallic oxide, sulphide, selenide or telluride, with the concomitant formation of the disulphide of the radical which formed a part 35 of the mercaptan.

In its broadest aspects, the invention comprises treating petroleum products such, for example, 40 as a distillate having a boiling point up to as high as 600° F. by passing the same through a body of brucite for the purpose of removing acid bodies therefrom while at the same time altering the sulphur compounds contained in this distillate by the expedient of adding dissolved sulphur to the same before it passes through the brucite, whereby the sulphur compounds which are present in the distillate in the form of mercaptans are converted into disulphides, so as 45 to render the same not only neutral but what is known in this art as "sweet to doctor". This term is applied to petroleum products and particularly to gasoline and kerosene, which will not give a positive reaction when tested with sodium 50 plumbite solution according to a test known as

"doctor test" described in standard text books on petroleum technology.

In the refining of petroleum products such as gasoline, kerosene, and the like, it is customary, in order to remove unsaturated compounds and 60 resins of resin-forming materials therefrom, to treat the same with sulphuric acid followed by washing in an attempt to remove as much of the acid as possible. However, the petroleum product thus treated cannot be rendered completely neutral unless means are employed to 65 remove the residual acid contained in the same. This is usually accomplished by treating the said petroleum product with sodium hydroxide or other alkali soluble in water. In accordance 70 with the present invention, however, a natural mineral, namely, brucite, which is magnesium hydroxide $Mg(OH)_2$ is employed. The gasoline or other petroleum product is passed through the brucite, preferably in an upward direction, 75 the brucite being in granular form.

In order to effect the alteration of sulphur compounds contained in the gasoline or other petroleum product treated, it has been found—in accordance with the present invention—that 80 the alteration of these sulphur compounds can be brought about and rendered certain by adding a solution of an element of the sulphur group to the gasoline, the most convenient one being sulphur itself, which is somewhat soluble in 85 gasoline and can hence be readily admixed with the petroleum product being treated. The reaction that takes place between the sulphur compounds in the gasoline, the magnesium hydroxide and the sulphur is substantially as follows: 90 $2RS + Mg(OH)_2 = (RS)_2Mg + 2H_2O$, the first compound formed being magnesium mercaptide. This mercaptide reacts with the free sulphur added to form magnesium sulphide and the disulphide of the radical R which had been combined with the sulphur in the mercaptan RS . $(RS)_2Mg + S = R—S—S—R + MgS$. The magnesium sulphide thus formed is substantially insoluble in the petroleum product and will hence be retained on the brucite, while the purified 100 petroleum product containing the disulphide is discharged from the brucite column neutral, "sweet to doctor" and will satisfactorily pass other required inspection tests for commercially marketable gasolines.

In carrying out the process on a commercial scale, it is advisable to employ a number of towers filled with brucite or with magnesium hydroxide produced artificially. The brucite, however, is commercially available at a low price and 110

is hence to be preferred for this purpose. The gasoline or other petroleum product to be treated is permitted to pass upward through a column of water preferably contained in a reservoir 5 in the tower immediately below the brucite and is then slowly percolated upward in this tower through the brucite, which is maintained upon a suitable foraminous retainer. At a point in advance of that where the gasoline or 10 other petroleum product enters the brucite tower, there is fed into it a solution of sulphur in gasoline, which gasoline in itself is "sweet to doctor". By analytical methods, which form no part of the present invention, the amount 15 of mercaptans contained in the petroleum product to be treated is determined; and from the above mentioned reaction, the amount of sulphur required to be added is calculated. The sulphur solution is fed into the product to be 20 treated by any standard means whereby its exact amount may be controlled; in other words, the sulphur solution is metered into the stream of petroleum product which is entering the brucite tower. An excess of sulphur should be 25 avoided, as the same might possibly—in the absence of sufficient mercaptans—be carried forward with the gasoline or other petroleum product, thus rendering the material unsatisfactory for recognized commercial uses.

30 While sulphur has been described as the specific material, it will, of course, be understood that the other elements of the sulphur group, such as oxygen, selenium, and tellurium or other materials possessing similar chemical properties, 35 will react similarly, although the cost of selenium and tellurium at the present time probably render their use commercially inadvisable.

The brucite, which is magnesium hydroxide, 40 is insoluble in water but is readily dissolved by acids, with the formation of the corresponding magnesium salts. When the acid and sulphur compounds containing petroleum product come in contact with the brucite, there will be 45 formed magnesium sulphate, magnesium sulphide, or magnesium hydrosulphide, all of which compounds are soluble in water but insoluble in the petroleum product or gasoline being treated. These products are hence deposited upon the brucite and after a period, depending entirely 50 upon the amount of impurities such as acids and sulphur compounds in the gasoline, render the brucite ineffective; whereupon it becomes necessary to regenerate the same so that it may again be used. For this reason, it is advisable to have a plurality of brucite towers into 55 any or all of which petroleum product may be directed, as the exigencies of operation require. For example, when the tower of brucite has lost its efficacy, it is cut out of service by shutting off 60 the supply of gasoline thereto and forcing water into the bottom of the tower slowly so as to force the gasoline or other petroleum product ahead of the water, whereby it is all removed from the tower and the tower filled with water instead. This operation is, of course, carefully watched so as to prevent water from mixing with the purified gasoline in the storage tanks which are connected with these purifying towers. When the brucite tower has been filled with 65 water, it is preferable to start pumping more water through the tower while discharging that already added, this further water being preferably hot, being heated either externally of the tower or by means of the injection of steam.

Water will dissolve and wash off the material deposited upon brucite, although the magnesium hydroxide itself is only soluble in acids. After the brucite has been regenerated in this manner, the water is drawn off and air or superheated steam blown through the brucite to blow out as much of the water as possible which may be adhering thereto.

80 The essential novelty in the process thus resides in the production of magnesium mercaptides from the mercaptans or organic hydro-sulphides contained in the petroleum product, and the secondary reaction whereby the said mercaptides are converted into disulphides by means of an oxidizing or sulphidizing reaction, 85 as shown in the hereinabove described reactions. Other means for introducing the sulphur may be employed, provided only that it may become dissolved in the product which is undergoing treatment; for instance, it would be considered 90 an equivalent to take a definite quantity of petroleum product and directly to add thereto the required amount of sulphur while agitating the petroleum product to cause the solution of the added element, whereafter the resultant sulphur- 95 treated product is passed upwardly through the brucite tower or towers. The sulphur may also be added in suitable amounts by passing the gasoline to be treated in whole or any part thereof through a small column of elemental sulphur 100 of suitable particle size, inserted in the system before the brucite column.

105 No apparatus has been described in connection with the present invention, as it relates purely and simply to a process which it is desired to 110 protect by Letters Patent and for which the following claims are made:

1. The process of altering mercaptans in gasoline which comprises adding elemental sulphur thereto and passing the resulting sulphur solution through a mass of brucite.
2. The process of purifying a liquid organic hydrocarbon which consists in dissolving an element of the sulphur group in the same and passing the resulting solution through a mass 115 of a magnesium compound soluble in acids.
3. The process of purifying a liquid organic hydrocarbon which consists in dissolving an element of the sulphur group in the same and passing the resulting solution through a mass of 120 magnesium hydroxide.
4. The process of purifying a liquid organic hydrocarbon which consists in dissolving an element of the sulphur group in the same and passing the resulting solution through a mass of 125 magnesium hydroxide.
5. The process of purifying gasoline which comprises dissolving sulphur in purified gasoline, adding said solution to a stream of impure gasoline that is to be purified, and passing the resultant mixture through a mass of granular brucite.
6. The process of rendering a petroleum distillate sweet to doctor which comprises passing the same through a mass of sulphur, then 130 through a body of water, and then through a mass of magnesium hydroxide.
7. The process of rendering a petroleum distillate sweet to doctor which comprises mixing the same with an element of the sulphur group and passing the resultant mixture successively through a body of water and a mass of magnesium hydroxide.
8. The process of rendering a petroleum distillate sweet to doctor which comprises mixing 135

the same with an element of the sulphur group and passing the resultant mixture successively through a body of water and a mass of brucite.

9. The process of purifying petroleum products containing mercaptans and similar sulphur compounds which consists in adding sulphur thereto and passing the resultant mixture through a mass of material consisting solely of magnesium hydroxide containing substantially no adsorbed water.

10. The process of changing mercaptans in fluid petroleum products which consists in converting said mercaptans directly into magnesium mercaptides by interaction with a mass of

magnesium hydroxide and, while in contact with said hydroxide, converting said mercaptides into the disulphides of the radical of said mercaptans by treatment with an oxidizing agent of the sulphur group.

11. The process of purifying petroleum products containing mercaptans so as to convert said mercaptans into organic disulphides which consists in treating said products with sulphur while passing through a mass of granulated magnesium hydroxide containing substantially no adsorbed water.
